Inventor,
Geo W. Chandler

United States Patent Office.

GEORGE W. CHANDLER, OF FITCHBURG, ASSIGNOR TO HIMSELF AND JOHN G. FOLSOM, OF WINCHENDON, MASSACHUSETTS.

Letters Patent No. 93,054, dated July 27, 1869.

IMPROVEMENT IN BALANCE-SCALES.

The Schedule referred to in these Letters Patent and making part of the same.

Know all men by these presents:

That I, GEORGE W. CHANDLER, of Fitchburg, in the county of Worcester, and Commonwealth of Massachusetts, have invented certain new and useful Improvements in Balance-Scales; and I do hereby declare that the following is a full, clear, and exact description of the same, reference being had to the accompanying drawings, forming a part of this specification, in which—

Figure 1 represents a side view of my improved balance-scale, and

Figure 2 represents a plan or top view of the same.

To enable those skilled in the art to which my invention belongs, to make and use the same, I will describe it more in detail.

In the drawings, the part marked A is the frame, the base B of which is cast hollow or open on the lower side, while the upright post C is also cast hollow, as indicated in the drawings by dotted and broken lines.

The pan or receptacle D, in which the articles to be weighed are placed, is supported on the forked stand E, which, in turn, is supported on the upper end of rod F, the lower end of which is provided with a screw-thread, to receive the thread of the joint-piece a, which is hinged to the adjusting-nut piece b, through which the rear end of the rod G passes or is screwed, the front end of rod G being held in place by the pin or pivot d.

The upper end of rod F is provided with a neck-piece, H, in which are secured the pivots or knife-edges c, which pass through holes in the rear ends I I of the beam J, which is supported in the curved standards K K of the cap-piece L, fastened to the top of the upright part O of frame A.

The front of beam J is hinged to the upper end of rod M, the lower end of which rod is hinged to the knife-edged lever-piece N, the front end of which is hinged between the stands e e, on top of the front post Q of frame A, all as fully indicated in the drawings.

P is the balance-weight, suspended to the front end of lever Q, the rear end of which is hinged between ear-pieces f f, fastened to the upright post O. The under side of the lever Q is smooth, and curved to correspond with the curved knife-edge g of the piece N, but wide enough to render the slipping laterally of the edge of lever N from its surface impossible.

R is the index-plate, the lower end of which is fastened to the front of frame A, while the upper curved end is graduated, to indicate the weight of the article being weighed.

It will be seen that as the arm or lever Q is raised, as indicated in red lines, fig. 1, by the article placed in the receptacle D, its leverage or resistance is greatly increased.

It will be understood that different weights can be added to the balance-weight P, the same as in the use of common scales, when the weight of the article cannot be indicated by the arrangement shown in the drawings.

By the use of the curved levers N and Q, as shown, a cheap and convenient pair of scales is produced, which possesses all the advantages of both the spring and lever-scales.

As the front end of rod G is held from turning, by means of the pin d, there is no liability of nut b working out of place, and yet it can be readily adjusted by simply removing pin d and turning rod G.

Having described my improved balance-scale,

What I claim therein as new and of my invention, and desire to secure by Letters Patent, is—

1. The combination of the knife-edged lever N with the smooth-faced lever Q, for varying the leverage of a balance-scale, substantially as set forth.

2. The combination, with rods F and G, and frame A, of the joint-pieces a b and pin d, substantially as and for the purposes set forth.

GEO. W. CHANDLER.
